[57] CLAIM

The ornamental design for an identification bracelet, as shown and described.

DESCRIPTION

FIG. 1 is a top perspective view of an identification bracelet showing our new design;

FIG. 2 is a bottom perspective view thereof;

FIG. 3 is a top plan view thereof;

FIG. 4 is a bottom view thereof;

FIG. 5 is a side elevational view thereof;

FIG. 6 is a side elevational view of the side opposite of that shown in FIG. 5;

FIG. 7 is a side elevational view as seen from the left side of FIG. 5;

FIG. 8 is a side elevational view as seen from the right side of FIG. 5;

FIG. 9 is a bottom perspective view of the present invention in an open position; and,

FIG. 10 is a top perspective view.
